UNITED STATES PATENT OFFICE.

FREDERICK A. RAY, OF MARYLAND, NEW YORK.

CAR-COUPING.

SPECIFICATION forming part of Letters Patent No. 275,943, dated April 17, 1883.

Application filed November 24, 1882. (No model.)

To all whom it may concern:

Be it known that I, FREDERICK A. RAY, a citizen of the United States, residing at Maryland, in the county of Otsego and State of New York, have invented a new and useful Self-Acting Car-Coupling, of which the following is a specification, reference being had to the accompanying drawings, forming part thereof.

My invention consists in the construction of a metallic tongue, &c., suitably arranged in the mouth of each draw-head on railroad-cars, whereby they are made self-coupling; and this invention can readily and at slight expense be applied to the draw-heads of cars now in general use.

Figures 1 and 2 are views of the draw-heads through the center, showing the several parts of my invention in a working position. Fig. 3 is a horizontal plan view of the tongue, which is constructed in width to nearly fill the draw-head. Fig. 4 is a small pin used for holding up the tongue when required.

A are the draw-heads, constructed in the usual way, with the addition of a couple of spurs or teats inside, which connect the draw-head and tongue. The draw-head may be constructed with the square chamber or cavity lower at the back end than at the front, for the purpose of elevating the end of the link with and without using pin G; also, at the front end of the draw-head, under the chamber and of the same width, a place cut out for the purpose of lowering the end of the link when required.

B is the tongue. It is constructed to pass under the spurs when put into the draw-head, and, when used in coupling the back end, is slightly raised and hitches onto said spurs, there being cavities in the tongue for that purpose. There is also a cavity in the back end of the tongue to receive and hold the link in position, the back end of said tongue being constructed much heavier than the front.

C is an elongated slot in the tongue, through which the coupling-pin D passes.

E are spurs or teats—one on each side inside the draw-head—which fit into the cavities in the tongue, and thus connect them together.

F is the coupling-link by which the cars are attached together.

G is a small pin attached on the outside the draw-head, for the purpose of being put through suitable holes in said draw-head to raise and hold up the tongue and coupling-link when needed, and in coupling high and low cars.

To use my invention the tongue is raised onto the spurs, the coupling-pin is put into position on the draw-head, the lower end of said pin resting on the top of the tongue, as shown by Fig. 1. In the opposite draw-head to be attached the tongue, link, and coupling-pin are all put in, the tongue and link are held at the desired height to enter the opposite draw-head by pin G, and when brought together the end of the link of Fig. 2 strikes the back part of the tongue of Fig. 1, forcing it back, permitting the coupling-pin to drop through the link, and the cars are coupled.

To attach my self-coupler to cars now in use, drill through the draw-head on each side, put in pins which will protrude inside said draw-head sufficient to make spurs to connect the draw-head and tongue; also drill holes for and supply with pins G and tongue B, which can be done at small expense and is all that is required.

What I claim as my invention, and desire to secure by Letters Patent, is—

The tongue B, spurs E, and pin G, constructed, arranged, and combined with the draw-head, as and for the purposes specified.

FREDERICK A. RAY.
